HIGH FREQUENCY ELECTRICAL SWITCH
DETAILJoseph F. Frese, Baltimore, Md., assignor to
Monitor Controller Company, Baltimore, Md.,
a corporation of MarylandOriginal application August 5, 1933, Serial No.
683,861. Divided and this application July 23,
1936, Serial No. 92,261

5 Claims. (Cl. 200—171)

My invention relates broadly to electrical switches and more particularly to a construction of switch arm for use in high frequency switch systems.

5 This application is a division of my copending application Serial Number 683,861, filed August 5, 1933, for "High frequency electrical switch and contactor system", now Patent Number 2,080,861, issued May 18, 1937.

10 One of the objects of my invention is to provide a construction of electrical switch arm offering minimum electrical capacity and subject to minimum losses when employed in high frequency circuits.

15 Another object of my invention is to provide a construction of switch arm affording a broad contact area at the contact surfaces thereof, and a low-loss connection at the pivoted end thereof.

20 Still another object of my invention is to provide a switch arm constituted by a tubular conductor having a flattened portion at one end affording contact mounting means, the tubular construction of the switch arm being particularly meritorious in high frequency electrical circuits.

25 A further object of my invention is to provide a switch arm constituted by a tubular conductor adapted to be pivotally mounted adjacent one end thereof, and having a flexible connector secured at the pivoted end thereof for effecting a low-loss connection thereto.

Other and further objects of my invention reside in the construction and adaptation of the switch arm hereinafter more fully described with reference to the accompanying drawing in which:

30 Figure 1 is a side elevation of the switch arm of my invention; Fig. 2 is a plan view of the same; Fig. 3 is a detailed vertical section taken adjacent the pivotal end of the switch arm and shows the flexible connector secured in the tubular switch arm; Fig. 4 is a cross-sectional view taken on line 4—4 in Fig. 3; Fig. 5 is an end elevation of the switch arm of my invention, looking in the direction of the line 5—5 in Fig. 1; and Fig. 6 is a general view of the switch arm of my invention as mounted for operation in a high frequency electrical switch.

35 The switch arm in a high frequency switch system is a critical unit. The other elements of a high frequency electrical system may be more or less easily designed for efficient operation at high frequencies, but the switch arm, because of the mechanical considerations attending its mounting and its actuation, presents particular problems affecting its efficient operation in a high frequency electrical system. The tubular switch arm of my invention is highly efficient in operation, carrying high frequency currents with minimum loss and capacity effects.

Referring to the drawing in more detail the switch arm of my invention comprises a tubular member 16, substantially elliptical in cross-section, adapted to be pivotally mounted adjacent one end, and having contacts on the other end. 5 I provide means intermediate the pivoted end and the end carrying the contacts for the connection of actuating means to shift the switch arm to selected positions. The tubular member 16 is provided at one end with a plug 18, as 10 shown particularly in Figs. 3 and 4, and an aperture 17 is formed in the tubular member 16 and the plug 18 to provide a journal for pivotally mounting the switch arm. The tubular member has a flexible connector 19 secured in 15 positive contact therewith by means of the plug 18, as shown in Figs. 3 and 4. The flexible conductor is prevented from being pulled out by the knots shown, or other suitable enlargements on the conductor 19. The plug 18 may be brazed 20 or welded in place in order to secure the flexible conductor permanently in place; or the plug may have only a force fit in the tubular member whereby it may be removed for replacement of 25 the flexible conductor.

The other end of the tubular member 16 is 25 flattened in the direction of the major axis of the elliptical cross-section, forming flat faces in planes parallel to the minor axis of the elliptical cross-section as shown at 21 in Figs. 1, 30 2 and 5, and contacts 22 are mounted thereon in any convenient manner. The form of switch arm shown is intended for operation in a double-throw switch system, such as shown in Fig. 6, and accordingly two contacts are shown, one on 35 each side of the flattened portion 21. The broad faces of the flattened portion afford adequate space for the mounting of contacts having large contact areas for reducing the contact losses in the switch.

40 As noted, the tubular member 16 is substantially elliptical in cross-section, as shown particularly in Fig. 4, and the rigid mounting of the plug 18 therein is thus facilitated. Furthermore, the pivotal mounting of the switch arm at the aperture 17 is also improved thereby, as the aperture 17 extends in the direction of the minor axis of the elliptical cross-section. In addition, the switch arm is apertured, as at 20, between the ends and in the direction of the 45 minor axis of the elliptical tubular member, to provide a journal for the pivotal connection of actuating means with the switch arm, as shown in Fig. 6.

45 In Fig. 6, I have shown a single pole, double 50 throw, high frequency electrical switch assembly, employing the switch arm of my invention. Reference character 1 designates the base on 55 which the parts of the high frequency switch-

ing system are mounted. Reference character 2 designates a bracket structure arranged at each end of the base in spaced relation thereto and secured by means of belts 4 extending 5 through spacer members 3 and secured to the brackets 2. Brackets 2 are secured to a ceiling, wall or panel structure indicated at 5. The base 1 is apertured in predetermined positions to receive socket members 6 which serve as supports for the dielectric standards. I employ a dielectric standard consisting of "Micalex" in which minimum dielectric losses occur by reason of the arrangement of the contact and pivot fittings with respect to the standards. It will be 10 noted that all mechanical stresses on the dielectric standards are produced longitudinally of the standards so that mechanical sheer stresses are reduced to a minimum. The sockets 6 are maintained in position with respect to base 1 15 by bolt members 7.

The dielectric standard 8 is mounted in one of the sockets 6 and provides a dielectric support for the pivot of the high frequency switch arm. The dielectric standard 9 is carried in the 20 other of the socket supports and provides a mounting means for stationary contacts engageable by the contacts on the switch arm.

A fitting 10 is mounted on the extremity of the dielectric standard 8 by means of bolt 11. 30 The fitting 10 supports the pivot pin 15 which passes through the aperture 17 in the tubular member 16. The flexible conductor 19 is held between the lug 12 and fitting 10 by the bolt 11 which extends into the lug 12. Conductor 14, 35 from the high frequency circuit, forms a positive connection through the lug 12 and the flexible connector 19 with the tubular conductor 16, thereby avoiding the loss of high frequency energy incident to connection through the pivotal mounting.

Stationary contact systems are mounted in spaced, selectively operative positions on the dielectric standard 9. Each contact system includes a contact 10 yieldably carried on an arm 45 66 and connected through a flexible conductor 71. Lugs 57 and 59 are connected to the flexible conductors 71, and to their respective circuits through conductors 58 and 60 respectively. The contacts 22 on either side of the flattened portion 21 of the arm 16 are adapted to engage 50 either of the contacts 70. The switch arm is pivotally connected with insulation member 24 by means of pin 23 extending through the aperture 20 in the tubular member 16. The insulation member 24 constitutes actuating means and 55 may be automatically or manually operated. The apparatus shown connected with the actuating member 24 is part of the automatic, motor operated, switch control system forming the subject matter of my copending application Serial No. 683,861, supra, of which this application is a division.

The switch arm construction of my invention has been found highly practical in production and efficient in operation, and while I have described my invention in certain preferred embodiments, I desire that it be understood that modifications may be made and that no limitations upon my invention are intended other than are imposed by the scope of the appended claims.

70 What I claim as new, and desire to secure by Letters Patent of the United States, is as follows:

1. In a high frequency electrical switch, a switch arm comprising a tubular conductor, a flexible connector extending within one end of said tubular conductor, a plug disposed in said tubular conductor at the said end thereof and adapted to secure said flexible connector in positive connection with said tubular conductor, and a contact on the other end of said switch arm, said tubular conductor and said plug being apertured for pivotally mounting said tubular conductor. 10

2. In a high frequency electrical switch, a switch arm comprising a tubular conductor of substantially elliptical cross-section, the walls of one end of said tubular conductor being flattened into intimate contact on a line parallel to the minor axis of the elliptical cross-section of said tubular conductor, contacts mounted on the faces of the flattened end of said conductor, said conductor having apertures therethrough on the minor axis of the elliptical cross-section thereof, one of said apertures affording a pivotal mounting for said switch arm, and the other of said apertures affording a connection for actuating means for said switch arm, and a flexible connector secured to said tubular conductor for making positive electrical contact therewith. 15

3. In a high frequency electrical switch, a movable switch arm for conducting high frequency currents comprising a hollow tubular conductor having a large surface area for the distribution of high frequency currents transmitted by said member, a braided flexible connector knotted at the end thereof and having the knotted end disposed in one end of said tubular conductor, a plug having a channel for said connector mounted in said tubular conductor for maintaining said connector in intimate contact relation with said tubular conductor, said plug being cooperative with the knotted end of said connector for retaining said connector in position, and a contact carried by the opposite end of said tubular conductor and having a large contact area for passing current through said switch arm with low contact resistance. 30

4. In an electrical switch, a switch arm comprising a tubular conductor of substantially elliptical cross-section, opposite sides of said tubular conductor being flattened into contact with each other at one end of said conductor, a flexible connector looped and having the end portions thereof disposed in the opposite end of said conductor in the recesses at opposite ends of the major axis of the elliptical cross-section of said conductor, a plug having recesses for said connector and shaped to fit within the open end of said conductor between the end portions of said connector, said conductor and said plug being centrally apertured on the minor axis of the elliptical cross-section of said conductor, and a pin member mounted in the aperture for maintaining said plug in position and pivotally mounting said tubular conductor for movement in the direction of the major axis of the substantially elliptical cross-section thereof. 50

5. In an electrical switch, a switch arm as set forth in claim 4 wherein the ends of said flexible connector are knotted within said tubular conductor for coaction with said plug in securing said connector in position. 60

JOSEPH F. FRESE. 70
